[57] CLAIM

The ornamental design for a combined food and beverage container, as shown and described.

DESCRIPTION

FIG. 1 is a bottom side perspective view of a combined food and beverage container showing our new design; FIG. 2 is a bottom plan view thereof; FIG. 3 is a side elevational view thereof; and FIG. 4 is a top plan view thereof.

The design is a figure of revolution and all side elevational views are identical to that of FIG. 3.

FIG. 1

FIG. 2

FIG. 4

FIG. 3
